UNITED STATES PATENT OFFICE.

TAYLOR W. HEINTZELMAN, OF SACRAMENTO, AND JAMES G. CAMP, OF OAKLAND,
CALIFORNIA.

AIR-FEEDING APPLIANCE FOR OIL-BURNING STEAM-BOILERS.

No. 910,285.

Specification of Letters Patent.

Patented Jan. 19, 1909.

Application filed September 19, 1907. Serial No. 393,622.

To all whom it may concern:

Be it known that we, TAYLOR W. HEINTZELMAN, of Sacramento, in the county of Sacramento and State of California, and JAMES G. CAMP, of Oakland, in the county of Alameda and State aforesaid, have jointly invented a certain new and useful Improvement in Air-Feeding Appliances for Oil-Burning Steam-Boilers, of which improvement the following is a specification.

Our present invention relates to, and is an improvement in, oil burning apparatus of the general character of that set forth in Letters Patent of the United States Nos. 15 830,833 and 861,515, granted and issued to us under dates of September 11, 1906 and July 30, 1907, respectively, and its object is to provide means whereby the current of air drawn into the firebox by the exhaust 20 will be divided and diverted and the objectionable noise attendant upon its direct traverse through the door opening be prevented; the air be somewhat heated before entering the firebox; and injury to enginemen and 25 firemen, from "flashing" resulting from carelessness or inexperience of firemen be more effectually prevented than heretofore.

The improvement claimed is hereinafter fully set forth.

30 In the accompanying drawings: Figure 1 is a transverse section through an air feeding appliance embodying our invention, on the line *a a* of Fig. 3; Fig. 2, a horizontal section on the line *b b* of Fig. 3; and Fig. 35 3, a vertical longitudinal central section through the appliance complete, and through the adjoining portion of the rear water wall of a steam boiler firebox to which it is attached.

40 Our improved air feeding appliance is, similar to those set forth in our Letters Patent Nos. 830,833 and 861,515 aforesaid, herein shown as connected to the rear water wall, 3, of the firebox of a tubular steam 45 boiler, and as adapted to control the supply of air thereto through an air supply passage, 24, formed in said rear water wall, and to change the direction of the current of air supplied through said passage, by a deflect- 50 ing plate, 27.

The structural features of improvement in an air feeding appliance of the above general type which constitute our present invention will now be described.

In the practice of our invention, we provide a frame, 24^a, which corresponds substantially in contour with the air supply passage, 24, and is secured by bolts or rivets, in the ordinary manner, to the rear water wall, 3, of a firebox, surrounding and forming an outward extension of the passage, 24. This passage may either be one specially formed in the rear water wall, or in application to a steam boiler designed for, or previously used with, solid fuel, it may be the ordinary door opening. An air feeding hood, 25, which is closed at its top and sides, and (except as to controlled openings hereinafter described) at its back and bottom, and is partially open at its front, and which has its rear wall outwardly inclined, is connected to the frame, 24^a, preferably, as shown, by being hinged thereto, the hood, in such case, being provided with lugs, 28, on one side, through which and through lugs, 24^b, on the frame, a hinge pin, 29, passes, and with a lug, 28^a, on its opposite side, through which passes a pin, 30, fixed to the frame, the hood being held up to the frame by any suitable fastening, as a key, 31, fitting in the pin, 30. /

A vertical front plate, 25^c, extends across the hood, 25, at its end which abuts against the frame, 24^a, throughout the major portion of its height, and the bottom of the hood is closed, from the front plate rearwardly to about the middle of its length, by a bottom plate, 25^d, which reduces the size of a lower opening and weight of damper, 26. A sanding tube, 32^a, which is open at each of its ends, extends from the front plate, 25^c, to the rear wall of the hood, and a transverse division plate, 25^b, extends across the hood, projecting downwardly from the top thereof to or near the axial plane of the sanding tube, and forming a semi-circular chamber having an opening, 25^e, leading into passage 24. The rear end of the sanding tube is normally closed by a cover plate, 33, which is suspended on a pin, 34, fixed in the rear wall of the hood, and which may be swung upon the pin when desired, as in the construction shown in Patent No. 861,515, aforesaid, to uncover the rear end of the sanding tube, 32^a, for the purpose of introducing sand into the firebox to free the tubes from deposits of carbonaceous material. A dead air space is

formed between the plate 25^b, and the rear wall of the hood for the purpose of keeping said wall cool.

The area for the passage of air through 5 the open portion of the bottom of the hood at the rear of the bottom plate, 25^a, and thence to and through the upper air supply passage, 24, is controlled and varied as required, by a damper or regulator, 26, which 10 is pivoted at its rear end to the rear wall of the hood, by pins, 26^e, passing through lugs, 26^e, on the damper, and corresponding lugs on the hood. By suitable movement and adjustment of the damper, relatively to the 15 axes of the pins, 26^e, the opening in the bottom of the hood may be closed, either completely or to any lesser degree, as desired.

A baffle or deflecting plate, 27, the function of which is to deflect the current of air 20 entering the firebox through the upper air supply passage, 24, downwardly towards the burner, is connected to the top of the frame, 24^a, and extends therefrom, in downwardly inclined position, through the passage, 24^a, into the firebox. The deflecting plate corresponds, in all essential particulars of construction and connection to the frame, 24^a, with that set forth in Patent No. 861,515 aforesaid, and not forming, in 25 and of itself, part of our present invention, need not be herein at length described.

The operative advantages of our present invention, relatively to prior constructions, in which the traverse of air to the firebox 30 is substantially direct and unobstructed, will be obvious to those familiar with oil burning locomotive practice. The division of the entering current of air by the central sanding tube and transverse division plate, 35 and its retardation and change of direction by the bottom plate, division plate, and front plate, prevent the objectionable noise ordinarily experienced, and also cause the air to be preheated to some extent before 40 entering the supply passage. The front plate bottom plate, and damper also prevent any direct outrush of flame from the firebox, in case of "flashing" and correspondingly protect the men on the foot plate of 45 the locomotive from injury therefrom.

We claim as our invention and desire to secure by Letters Patent:

1. The combination, with a steam boiler firebox rear wall having an air supply passage, of a frame connected to the firebox 55 wall and surrounding said passage, an air feeding hood connected to said frame and comprising a rear wall, a front plate closing the lower portion of its end adjoining the frame and a bottom plate closing the forward portion of its bottom, a division plate between and substantially parallel to the rear wall and front plate, and extending from the top to the center of the hood, and a pivoted damper controlling the opening in rear 60 of said bottom plate.

2. The combination, with a steam boiler firebox rear wall having an air supply passage, of a frame connected to the firebox wall and surrounding said passage, an air feed 70 hood connected to said frame and comprising a rear wall and a front plate closing the lower portion of its end adjoining the frame, an open ended sanding tube extending from said plate to the rear wall of the hood, and 75 a division plate extending from the top of the hood to the sanding tube, and a movable cover plate controlling the outer end of the sanding tube.

3. The combination, with a steam boiler 80 firebox rear wall having an air supply passage, a frame connected to the firebox wall and surrounding said passage, an air feed hood connected to said frame and comprising a rear wall and a front plate closing the 85 lower portion of its end adjoining the frame, a bottom plate closing the forward portion of its bottom, an open ended sanding tube extending from the front plate to the rear 90 wall of the hood, and a division plate extending from the top of the hood to the sanding tube, a movable cover plate controlling the outer end of the sanding tube, and a pivoted damper controlling the opening in rear of the bottom plate.
